UNITED STATES PATENT OFFICE.

AARON KEEVER AND FREDRICK REMY, OF ASHLAND, OHIO.

WAGON-BRAKE.

SPECIFICATION forming part of Letters Patent No. 353,685, dated December 7, 1886.

Application filed August 14, 1886. Serial No. 210,869. (No model.)

To all whom it may concern:

Be it known that we, AARON KEEVER and FREDRICK REMY, citizens of the United States, residing at Ashland, county of Ashland, and State of Ohio, have invented certain new and useful Improvements in Wagon-Brakes; and we do hereby declare the following to be a description of the same and of the manner of constructing and using the invention in such full, clear, concise, and exact terms as to enable any person skilled in the art to which it appertains to construct and use the same, reference being had to the accompanying drawings, forming a part of the specification, the principle of the invention being herein explained and the best mode in which we have contemplated applying that principle, so as to distinguish it from other inventions.

Our invention is an improvement in wagon-brakes, as hereinafter more fully described.

In the drawings, Figure 1 is a plan view of the invention. Fig. 2 is a side elevation of the same.

A is a cross-bar rigid on the hounds B of the rear truck.

C is the brake-bar extending across from wheel to wheel, and suspended under the hounds to cross-bar A by loose links c. Said bar is provided with brake-blocks, as usual.

D is a rock-shaft journaled in staples d, secured to the rear truck-axle. Said shaft has shoulders d', to prevent its lateral movement in the eyes of the staples d. The inner end of said shaft has the crank-arm d'', at the extremity of which is loosely pivoted the link E, said link rigidly attached to brake-bar C.

The outer end of rock-shaft D is provided with arm e, projecting from shaft D in a virtually opposite direction from crank-arm d''. At the outer extremity of arm e is pivoted the ratchet-link F, adapted to lock in with lip f, rigid on cross-bar A. The forward extremity of ratchet-link F is loosely hooked in an eye formed in lever G at a point somewhat re-

40 moved from the fulcrum-point of said lever on cross-bar A. Said lever extends horizontally outwardly from its fulcrum-point, and may be of any desired length, and is also suf-

ficiently loosely geared at its said fulcrum-point to permit ratchet-link F being easily 50 lifted from its locking with lip f.

The obvious working of this brake device, as described, is such as to demand no further attempted description.

We pass, therefore, immediately to what we 55 claim, as follows:

1. The combination, with brake-bar C and cross-bar A, of a hand-lever, ratchet-link F, and intermediate mechanism connecting the latter with the brake-bar, said ratchet-link 60 locking with said cross-bar, substantially as set forth.

2. The combination, with brake-bar C and cross-bar A, of a hand-lever, ratchet-link F, and intermediate mechanism connecting the 65 latter with the brake-bar, said cross-bar provided with lip f, with which said ratchet-link engages, substantially as set forth.

3. The combination, with cross-bar A, rigidly secured to the hounds, of a lever, G, pivoted to said cross-bar, and ratchet-link F, interlocking with said cross-bar, substantially as set forth.

4. The combination, with brake-bar C, connected by link E to rock-shaft D, of cross-bar 75 A, connected to said rock-shaft by ratchet-link F and lever G, said link adapted to lock in with lip f on said cross-bar, substantially as set forth.

5. The combination, with brake-bar C, linked 80 to rock shaft D, and cross-bar A, provided with lip f, and lever G, of ratchet-link F, connecting said lever with said rock-shaft, substantially as set forth.

6. The combination, as described, of brake-bar C, link E, rock-shaft D, ratchet-link F, and cross-bar A, provided with lip f, and lever G, substantially as set forth.

In testimony that we claim the foregoing to be our invention we have hereunto set our 90 hands this 7th day of August, A. D. 1886.

AARON KEEVER.
FREDRICK REMY.
